UNITED STATES PATENT OFFICE

2,049,949

APPARATUS FOR PRODUCING SUDORIFEROUS VAPOR BATHS

Jacopo Diena, Paris, France

Application June 5, 1933, Serial No. 674,451
In France June 7, 1932

7 Claims. (Cl. 21—18)

My invention relates to improvements in generators for supplying superheated vapor to a chamber of any construction used for sudoriferous vapor baths, and is an improvement over my 5 Patent 1,822,615, dated September 8, 1931.

Briefly stated, the present invention aims to (1) improve upon the construction disclosed in my patent aforesaid by providing for facilitated regulation of the bath temperature and the temperature of the superheated vapor; (2) the provision of means for properly proportioning the superheated vapor and hot air; (3) by the provision of novel means for regulating not only the quantity of mixture but also the degree of humidity of the same, and likewise the degree of heat of the hot air and the quantity of the latter; (4) by the provision of means whereby hot air may be discharged directly to the atmosphere without going to the treating chamber; (5) by 10 keeping the products of combustion from the burner or the like out of the treating chamber; (6) by providing means for regulating both the quantity and temperature of the heated air and vapor entirely independently of one another; and (7) finally by providing novel means whereby the 15 draft to the burner element may be readily regulated.

The foregoing objects are obtained by certain novel features of construction, combination and arrangement of parts to be hereinafter described and claimed, reference being had to the accompanying drawing in which:

Figure 1 is a cross sectional view through a unit embodying my invention and illustrating a portion of a wall of a treating chamber, and—

Figure 2 is a similar view illustrating a modified form of vapor generator unit.

Referring to Figure 1 by reference characters, numeral 1 designates the water vessel in which 40 steam is generated, such vessel being supported by a mounting comprising a frame 2 whose upper portion provides a rest for the vessel 1. The burner 3 is supported by the inturned lower portions of the frame 2 and the parts 1, 2 and 3 are 45 inclosed in a casing 8 having a flanged base as shown, the walls of the casing 8 being spaced from the walls of the water vessel 1.

Projecting up into the steam generator or water vessel 1 are the inlet ends of the tubes 5 which extend out through the bottom of the vessel 1. At least one of the tubes 5 is provided with a coil 6 above the burner 3. The tubes 5 extend upwardly alongside the vessel and project outwardly 55 through the flue 10 which extends through a hole

in the wall 18 of the treating chamber wherein will be the person to be subjected to the bath.

Within the flue 10 and located below the tubes 5 is a heater element 13 which may be of any desired form and which is designed for superheating the steam vapor passing outwardly from the vessel 1 through the tubes 5. The casing 8 is provided with a closure 9, as shown.

The end of the flue 10, inwardly of the treating chamber wall 18, is provided with the top outlet 12 into the treating chamber, the outer end of the flue 10 being closed as shown; and the tubes 5 having their ends directly upwardly as indicated at 7 so that such tube ends are arranged in a row and spaced from one another in the direction of the width of the outlet opening 12 of the flue 10. That is to say the upwardly bent ends 7 of the tubes are spaced from one another inwardly of the outer end of the flue 10 and in the direction of the wall 18.

In order to control the discharge of hot air from the flue outlet 12, and also to cut off the discharge of heated vapor from one or more of the ends 7 of the tubes 5, I provide the valve or sleeve member 17 which slides upon the exterior surface of the flue 10 and is adapted to be moved outwardly from the position shown to close off the end of one or more of the tubes 5 and also proportionately cut off a certain area of the opening 12 so as to restrict the same and diminish the volume of air that will pass outwardly. Surrounding the sleeve member 17 is an insulation sleeve 15 carried by the opening in the treating chamber wall 18. The purpose of this is to protect the treating chamber wall from the direct heat of the flue 10. It will be understood, of course, that the insulation sleeve 15 will admit of free movement of the valve sleeve 17.

Numeral 11 designates a plurality of air inlet openings in the casing 8 adjacent the base and about the burner 3. Externally of the casing there is provided the collar or valve element 16 which is adapted to be moved to regulate the inlet of air through the passages or openings 11. The burner 3 may be controlled by the regulating handle 14 or the like.

Located in the top 9 of the casing 8 is the valve 19 the purpose of which is to enable excess hot air to be let out into the atmosphere without going into the treating chamber. Thus regulation of valve 19 determines the proportion of hot air discharged out through the flue 10 for mixture with the vapor emanating from the discharge ends 7 of the tubes 5. Furthermore, when the sleeve 17 is moved to close substantially the

55

opening 12 and likewise to substantially cut off the outlet of vapor from the ends 7 of the tubes it will be apparent that valve 19 will also serve as an outlet or relief means for the excess vapor 5 or steam discharged through the ends 7 of the tubes 5.

In respect to the collar or valve member 16 it will be evident that when it is raised to partially cut off the entry of air through the openings 10 11 in the casing 8 the supply of air to the flue 10 will be diminished and furthermore where the burner 3 is a fuel burner the diminishment of air thereto by raising of the collar 16 to partially close openings 11 will mean that there will be less 15 air for combustion and in consequence the burner will not heat the water in vessel 1 to the extent that it would if openings 11 were fully open. Thus aside from the burner control member 14 it will be appreciated that collar 16 enables the 20 temperature of the fluid in vessel 1 to be regulated and consequently the temperature of the bath that is to be had within the treating chamber of which wall 18 is shown. It will be apparent that various proportions of hot air and vapor can 25 be obtained by regulation of valve 19 in the top 9 of casing 8 in relation to the regulation of sleeve 17 which controls the outlet of vapor and hot air through the outlet 12 of the flue 10.

Turning now to Figure 2, numeral 20 designates 30 standards supporting an inverted bell-like shell member 29 which is open at the bottom and has its upper end carrying the water vessel or tank 22. A cross member extending between the standards 20 carries the burner 21 which is disposed immediately below the vessel 22 for the purpose of heating the contents thereof.

Surrounding the shell 29 and spaced from the same at all points to define the passage 28 is a similar inverted bell-like shell 29a through the 40 upper end of which extends the upper end of the water vessel 22. The lower ends of the shells 29, 29a are spaced from the floor or support so as to admit air into the first-mentioned shell so as to support the combustion of fuel in the burner. 45 Also the elevation of the lower ends of the bell-shaped members 29, 29a from the floor permits the entry of air into the passage 28 between the bell-like shell members, this air being transmitted to a point for admixture with vapor as will be 50 presently explained.

Extending upwardly into the water vessel 22 through the bottom thereof are the inlet ends of the tubes 23, 23a. These tubes 23, 23a lead outwardly through the bottom of the water vessel 55 22 at a point adjacent one side of said vessel. From thence the tubes 23, 23a lead across the bottom of the vessel above the burner 21 and are coiled about one of the supports 20 as shown, the coils extending upwardly to a point adjacent 60 the top of the bell-shaped shell member 29. At this point the pipes 23, 23a lead outwardly into a passage 32. The outer end of the passage 32 receives the inlet end 33 of a discharge pipe for smoke.

65 The passage 32 is provided in a flue member 27 which is in part carried by each of the bell-shaped shell members 29, 29a and which has the partition 27a separating the passage 32 in which are located the vapor pipes 23, 23a from the 70 passage 34 which communicates with the air supply passage 28 opening from between the bell-shaped shell members adjacent the lower ends thereof.

The flue 27 provides an opening 26 leading into 75 the passage 34 at the outer end of the latter in-

wardly of the outer end wall of the flue; but the passage 32 of such flue is closed except for the outlet pipe 35 which carries off the products of combustion.

The outlet opening 26 in the upper portion of 5 the flue 27 leading from the passage 34, is adapted to be controlled by a slide member valve 30 which is controlled by means of a key member or handle 31.

Particular attention is directed to the fact 10 that the outer ends of the vapor tubes 23 are turned laterally and extend with a snug fit through holes in the partition member 27a which separates the flue passage 32 from the other passage 34. The upper ends of the tubes 23 are 15 designated at 25 and are disposed immediately below the opening 26 and are spaced from one another in the direction of the length of the passage 34 so that the slide 30 can be positioned to overlie one or both of the ends 25 of the tubes 20 23. Thus I can vary materially the mixture of heated vapor from the tubes 23 with the air in the passage 34, in addition to controlling the volume outflow of the vapor and air mixture through the opening 26 to a treating chamber 25 into which the flue 27 extends.

Especial note should be taken of the fact that the coils 24 of the vapor pipes 23, 23a are located in the path that the products of combustion and to some extent the flames from the burner 21 will 30 necessarily have to follow in order to reach the smoke pipe inlet 33 adjacent the outer end of the passage 32 of the flue 27. Thus the vapor from the fluid vessel 22 in the pipes 23, 23a will be superheated by the products of combustion and 35 flames traveling in the direction of the inlet to the passage 32 of the flue 27.

It is further to be noted that the vapor pipe 23a terminates short of the outer end of the passage 32 of the flue 27. The reason for this is to give 40 acceleration to the discharge of the products of combustion into the inlet 33 of the smoke pipe 35. It will be understood, of course, that the smoke pipe 35 will discharge into the open air and not 45 into the chamber (not shown) adjacent the right hand wall of the vapor supply unit casing 40.

It is further to be noted that there is provided adjacent the top wall of the passage 34 of the flue 27 a steam or vapor pipe 39 which is adapted to be controlled by a valve 37 adjacent the upper 50 end of the water vessel or steam generator 22. Thus when valve 37 is open there will be supplied additional vapor to the passage 34 of the flue 27 at a point adjacent the opening 26 and adjacent the outlet ends 25 of the vapor pipes 23. Furthermore, the steam or vapor pipe 39, not being subjected to superheating by the products of combustion as is the case with pipes 23, the opening of the valve 37 will reduce the temperature of the air and vapor mixture passing out 60 through the opening 26 in addition to giving the same greater humidity.

The water vessel 22 may be provided with a valve-controlled steam outlet pipe 38 in its top. A valve 38a is illustrated for control of the outflow of steam from the steam outlet pipe in the top of the water vessel 22. This valve 38a would be opened when it is desired to reduce the volume of steam or vapor supplied to the manifold passage 34 by the pipes 23. It will be appreciated 70 that when the valve 38a is fully opened, little or no vapor will be supplied to the manifold passage 34. In consequence a substantially dry hot air bath will be provided.

There may be provided within the water vessel 75

22 a receptacle 36 for receiving a preparation having therapeutic value; and under some circumstances this preparation may be subjected to heat without there having been placed in the vessel 22 water or any other liquid.

5 In respect to the form of the invention shown in Figure 2 it will be apparent that both the temperature and humidity of the vapor and air mixture discharged through the opening 26 may 10 be controlled by manipulation of the valve 38a of the steam outlet pipe 38 in the top of the water vessel 22. It will also be apparent that the 15 humidity of the air and vapor mixture can be further regulated by the manipulation of the valve 37 of the auxiliary vapor pipe 39 leading outwardly adjacent the upper wall of the passage 34 of the flue 27.

Comparing the devices of Figures 1 and 2, it is noted that each has control for the temperature 20 of the bath. For instance, in Figure 1, adjustment of collar 16, as mentioned, over portions of openings 11 cuts down the supply of air to burner 3 to reduce the amount of heat thrown out thereby and lower the temperature of vapor discharged 25 from pipes 5, besides reducing the flow of hot air in 10. Also, the additional superheater 13 contributes to this end; and likewise the valves 17 and 19 operated alone or in combination with one another.

30 Temperature regulation of the bath mixture supplied by the device of Figure 2 is had by use of the valve-controlled steam outlet pipe 38 from container 22; and also by use of the auxiliary supply pipe 39 carrying unsuperheated steam to outlet 26; and further control of the temperature 35 of the bath mixture and bath is had by manipulation of slide valve 30, corresponding to valve 17 of Figure 1.

As to regulation of humidity of bath mixture 40 supplied by the device of Figure 1, this can be accomplished by adjustment of 19 to let out air from 9; or by adjustment of 17 to cover the discharge end of one more of the steam pipes 5. In Figure 2, the valve controlled steam outlet pipe 39 from 22 to air outlet 26 enables the 45 humidity of bath mixture to be regulated; also valve 30 is operable to virtually shut off one or the other of steam pipe outlets 25.

Quantity regulation of supply of the mixture 50 is had by means of valve sleeve 17 and in Figure 2 by valve 30, 31. It is also noted that valve 17 in Figure 1, valve 30, 31 of Figure 2 have dual functions, in that each controls not only the quantity of heated air and vapor mixture applied to the bath, but also the humidity of said mixture by at 55 least partially cutting off steam flow from one or more of the pipe outlets 1, 25 respectively.

The described apparatus can be covered by a 60 suitable protecting envelope of wire gauze 40 traversed in a close manner by the flue 27, which latter will extend beyond such envelope. The apparatus may be placed in the chamber of treatment (not shown) inasmuch as the pipe or pipes 65 35 which carries off the products of combustion can be led out through a wall of the chamber of treatment. The wire gauze envelope 40 will protect the occupant from fire in case anything goes wrong with the burner in event that the apparatus is placed in the chamber of treatment 70 (not shown).

I claim:

1. An apparatus of the class described including a treating chamber and comprising, a standard located remotely from said chamber, heating means carried by said standard and above

the base thereof, a substantially bell-shaped member carried by the upper end of said standard and having its lower edge extending below said heater, a container for vapor producing material carried by the dome of said bell-shaped member above said heater, a second bell-shaped member superimposed on said first like member and spaced therefrom to provide an air chamber therebetween, a conduit connecting said air chamber with said treating chamber, a second conduit beneath said first conduit for the discharge of the combustion gases of said heater to the open air, vapor conducting tubes leading from said container through said second conduit to said treating chamber and the ends of said vapor tubes discharging into said first-mentioned conduit adjacent the discharge end thereof whereby to effect a mixing of the vapor and air for passage to said treating chamber.

2. In an apparatus for producing sudoriferous 20 baths, having a fluid receptacle, an air supply means and a heater for both of the same, an air outlet manifold leading from said air supply means and having an outlet orifice, fluid vapor pipes extending into said manifold and having 25 outlets opposite said orifice and spaced in the direction of the width of said orifice, and valve means for controlling the discharge through said orifice and movable to substantially shut off predetermined numbers of said vapor pipes whereby 30 to regulate both the quantity and humidity of the mixture discharged from said orifice.

3. The combination set forth in claim 2 and including a superheater in said manifold adjacent 35 said pipes.

4. In an apparatus for producing sudoriferous baths, having a fluid receptacle, an air supply means and a heater for both of the same, an air outlet manifold leading from said air supply means and having an outlet orifice, fluid vapor 40 pipes extending into said manifold and having outlets opposite said orifice and spaced in the direction of the width of the orifice, valve means for controlling the discharge through said orifice and movable to substantially shut off predetermined numbers of said vapor pipes whereby to 45 regulate both the quantity and humidity of the mixture discharged from said orifice, partition means dividing said outlet manifold in the direction of its length into upper and lower passages, the upper passage having communication with said air supply means and the lower passage having communication with said heater and being open to reception of the products of combustion therefrom, said vapor pipes leading into the second mentioned passageway of said manifold and extending upwardly through said partition in opposition to said orifice.

5. The combination set forth in claim 4, and an outlet for the products of combustion leading 60 from the outer end of the second-mentioned passageway, said pipes providing coiled portions arranged in the path of the products of combustion and between the burner and the inlet to the second-mentioned passageway of said manifold.

6. The combination set forth in claim 4, and an outlet for the products of combustion leading 70 from the outer end of the second-mentioned passageway, said pipes providing coiled portions arranged in the path of the products of combustion and between the burner and the inlet to the second-mentioned passageway for said manifold, and one of said vapor pipes terminating short of the outer end of said second-mentioned manifold 75 passage and discharging thereinto whereby to ac-

celerate the discharge of the products of combustion from said second-mentioned passage-way.

7. The combination set forth in claim 2, and
5 said vapor pipes passing below the bottom of said fluid receptacle whereby to effect a superheating of the vapor passing through said pipes, and an additional vapor pipe leading from the upper part

of said water vessel and outwardly through said manifold to a point adjacent said orifice and adjacent the outlets of said vapor pipes whereby to supply additional vapor for the bath which has not been superheated, and a control valve means for said last-mentioned vapor pipe. 5

JACOPO DIENA.
